(57) **CLAIM**

The ornamental design for a record player as shown and described.

DESCRIPTION

FIG. 1 is a first perspective view of a record player, according to a first embodiment of the invention.

FIG. 2 is second perspective view thereof.

FIG. 3 is a front elevation view thereof.

FIG. 4 is a rear elevation view thereof.

FIG. 5 is a left side view thereof.

FIG. 6 is a right side view thereof.

FIG. 7 is a top plan view thereof.

FIG. 8 is a bottom plan view thereof.

FIG. 9 is a first perspective view of a record player, according to a second embodiment of the invention.

FIG. 10 is second perspective view thereof.

FIG. 11 is a front elevation view thereof.

FIG. 12 is a rear elevation view thereof.

FIG. 13 is a left side view thereof.

FIG. 14 is a right side view thereof.

FIG. 15 is a top plan view thereof; and,

FIG. 16 is a bottom plan view thereof.

The broken lines depict portions of the record player that form no part of the claimed design.

1 Claim, 12 Drawing Sheets
